CAR TRUCK

Mark H. Martin, Reading, Pa., assignor to Birdsboro Steel Foundry & Machine Company, Birdsboro, Pa., a corporation of Pennsylvania

Application November 4, 1929, Serial No. 404,592

43 Claims. (Cl. 105—197)

My invention relates to car trucks and more particularly to the construction of the side frames, bolsters, the novel arrangement of the springs, and to the means for connecting these 5 parts together in a manner facilitating assembly and disassembly.

One object of my invention is an improvement in the construction of side frames involving the provision of a truss structure for strengthening 10 the frames and minimizing the deflection between the bolster columns under the increased loadings which are now becoming standard practice in the enlarging of the spring group above the standard A. R. A. nest of four springs.

15 A further object is to devise an enlarged spring group comprising seven springs in which the springs are so arranged as to retain the major portion thereof within a depth of bolster window opening which is not greater than that 20 now in use for a four spring nest, with a corresponding reduction in the overhang on the side frame and a saving in weight through an avoidance of any necessity for lengthening the spring plank and one side of the spring seat web of 25 the frame.

A further object is to devise a manner of arranging the springs of a seven spring group which does not require a width of bolster window opening greater than that for a six spring 30 group arranged in two rows of three springs each, with a consequent shortening of the bottom tie portion of the tension member and a stiffening of the same against deflection, and which group is further arranged for reduction 35 to a six spring group by extracting one spring without affecting the proper support of the bolster, or creating a faulty application of forces to the side frame.

40 A further object is to devise a method of connecting the bolster to the side frame which facilitates the disassembly of these parts for replacing wheels or the frame and whose exercise does not require the removal of the springs, spring plank and the bolster.

45 A further object is to provide a truck bolster in which the metal is disposed to increase the transverse and vertical strength thereof and also to avoid the creation of shrinkage cracks in the casting at the junction of the side walls with 50 the bottom and top of the bolster.

Side frames function generally as trusses and comprise a compression and a tension member, the latter in turn including the bottom tie portion between the bolster columns which is there- 55 fore subjected to tensile stress, considering the

side frame as a unit. In addition, this tie portion operates as a beam in the carriage of the spring load and likewise undergoes tensile and compressive stresses which are local in nature and superimposed on the principal tensile stress 60 in the frame. The result of this condition is that, particularly with enlarged spring groupings and the attendant increased loadings, the tie portion exhibits a deflection tendency with 65 ensuing fatigue in the metal.

It is one of the express objects of my invention to rigidify the bottom tie portion of the side frame while maintaining the usual operating clearances. Briefly, this result is accomplished 70 by the utilization of inner and outer truss structures which strengthen inwardly and outwardly the box section of the tie portion and also the spring plank shelves which extend laterally from the frame, this phase of my invention being described and illustrated in my copending application for a side frame, Serial No. 347,482, filed March 16, 1929. This form of construction lends itself readily to a wide variety of spring groupings without affecting the central thought 75 involved, but it is particularly useful in an arrangement where the major portion of the spring load is disposed along the longitudinal axis of the frame.

The spring group which forms an important 80 phase of the present invention consists of seven springs arranged in two rows of three springs each placed side by side in symmetrical relation to the window opening, with the seventh spring located inwardly of the frame toward the center 85 of the truck on the median line of the spring plank, or in a generally T-shaped formation in plan. Outwardly of the truck, therefore, the springs do not extend further than the customary nest of four springs so that it is unnecessary to lengthen the spring plank, or to increase 90 the depth of the spring seat web of the frame in that direction, with a corresponding saving in weight of these parts and a reduction in the overhang on the side frame. The arrangement 95 of the springs in the group is extremely versatile 100 in that the inner spring may be removed to reduce the group to a total of six springs, as the operative conditions may determine, without affecting the modified group as an adequate load sustaining structure within its capacity.

105 The manner of engaging the end of the truck bolster with the frame has been designed for the purpose of facilitating the assembly and dismantling of these parts in conjunction with the springs and spring plank. When the stand- 110

ard A. R. A. truck bolster or any bolster with integral guide lugs is used, the replacement of a pair of wheels or side frame requires a removal of the springs and spring plank and a dropping 5 of the bolster to the bottom of the window opening of the side frame. In my improved arrangement, which substitutes removable retaining plates carried by the frame and engaging with the bolster for the customary outer integral lugs 10 on the bolster, it is only necessary to first remove these plates and then block up the spring plank, springs and bolster in order to remove the frame. These plates perform the primary functions of the lugs as regards vertical guidance of the bolster and preventing outward lateral movement of the side frames in case of a wreck or other unusual operative conditions, and the carriage of the plates on the frame has been so arranged 15 as to permit the use of a bolster having integral lugs, if substitution is desired.

The invention also contemplates the disposition of the metal in the bolster castings which not only strengthens the unit in vertical and transverse directions, but also avoids the creation 20 of shrinkage cracks during cooling which are now occasioned by the junction of thin side walls with a relatively heavy bottom and top. This object is accomplished by making the metal adjacent the junction edges of a greater thickness 25 relative to that at the transverse neutral axis of the side walls and at the vertical neutral axis of the bottom and top. A modification of this distribution of metal is also employed in the side walls of the bottom tie portion of the 30 side frame tension member.

These and further objects of my invention will be set forth in the following specification, reference being had to the accompanying drawings and the novel means by which said objects 40 are effectuated will be definitely pointed out in the claims.

In the drawings:

Figure 1 is a side elevation of a portion of a car truck, partly in section, the journal boxes 45 and wheels being omitted and the springs being shown in diagrammatic outline.

Fig. 2 is a section along the line 2-2 in Fig. 1, looking in the direction of the arrows, and showing the manner of engaging the truck 50 bolster and side frame.

Fig. 3 is a section along the line 3-3 in Fig. 1, looking in the direction of the arrows, the springs being shown in dotted outline.

Fig. 4 is a section along the line 4-4 in Fig. 55 1, looking in the direction of the arrows, the bolster and springs being omitted.

Fig. 5 is a section along the line 5-5 in Fig. 4, looking in the direction of the arrows, and showing the internal truss arrangement within 60 the bottom tie portion of the tension member.

Fig. 6 is a partial view showing the under side of the tension member between the bolster columns.

Fig. 7 is an enlarged plan view of the spring 65 plate.

Fig. 8 is a section along the line 8-8 in Fig. 7, looking in the direction of the arrows.

Fig. 9 is a perspective view of a portion of the truck bolster.

Fig. 10 is a section along the line 10-10 of Fig. 9, looking in the direction of the arrows.

Fig. 11 is a diagrammatic representation of the system of loading as applied to one of the external trusses on the bottom tie member.

Fig. 12 is a view similar to Fig. 2 showing

the application of a standard truck bolster to my improved side frame.

The several views on the drawings illustrate portions of a car truck comprising a side frame 10 which, as illustrated, is of cast construction, but may be otherwise formed as desired without departing from the essential conception of the present invention. The frame 10 consists of the usual compression member 11 and tension member 12 which are joined by the usual bolster columns 13 disposed in spaced relation to define with said members a window opening 14 and a portion of the tension member 12 below said columns comprising a bottom tie member 15.

Said tie member is generally of box section 90 and includes an outer shelf 16 and an inner shelf 17 which extend laterally therefrom in a plane common with the upper web 18 of the section. The inner shelf 17 further includes a projecting portion 19 which is centrally disposed with reference to the bolster columns 13 and forms with the shelves 16 and 17, and the web 18 a spring supporting portion which is generally T-shaped in plan. Said shelves further include the customary bosses 20 which project upwardly therefrom and are received in suitable holes provided in a spring plank 21 which rests on said shelves and is determined in position by said bosses.

In order to strengthen the bottom tie portion 105 15 between the bolster columns 13, the following instrumentalities are provided. Flanges 22 project outwardly from the side walls of the member 15 and extend upwardly, from points which lie in a plane common with the lower web of 110 said member and also in a plane which is common with the vertical axial plane of the central spring group, as hereinafter described, towards the lower corners of the window opening, merging into the upper web 18 of the member, or 115 lateral extensions thereof, and extending around said corners and upwardly along said columns for a predetermined distance as at 23. Ribs 24 also project outwardly from the sides of the member 15 and extend vertically upward from 120 the lowermost points of the flanges 22 to the underside of the shelves 16 and 17, the rib which is disposed beneath the shelf 17 being carried almost to the inner edge of the projecting portion 19, as shown in Fig. 4, thus providing an 125 adequate support for said portion. There is thus formed on each outer side of the member 15 a two-panel truss in which the respective shelves form the compression members, the flanges 22 the tension members, and the ribs 130 24 the struts. Strengthening webs 25 may also be disposed below the flanges 22 in a plane common with the lower web of the portion 15 and extending from the mid point of said portion to merge into the side walls thereof, as 135 shown clearly in Fig. 6.

Additional strengthening means within the member 15 is furnished by a similar pair of integral trusses comprising flanges 26 which extend inwardly from the side walls of said section 140 toward each other and correspond generally with the position of the external flanges 22. Vertical ribs 27, corresponding in position with the external ribs 24, also project inwardly from the side walls of said section and extend from 145 the lower web thereof to the upper web 18.

As a further means of strengthening the box section of the bottom tie member 15, the distribution of metal in the side walls thereof is so arranged as to present a thickness on the 150

transverse neutral axis thereof which is less than the thickness which obtains at the junction of said walls with the upper and lower webs of the section, as indicated by the numeral 28 in Fig.

5 4. This disposition of the metal facilitates a more uniform cooling of the castings in the location noted with a consequent removal of any danger of creating shrinkage cracks, and this condition of distribution extends substantially 10 between the lines indicated by the numerals 29—29 which are disposed adjacent the bolster columns 13.

As before noted, one end of a spring plank 21 is carried on the shelves 16 and 17, as well as 15 the upper web 18 of the bottom tie member, and said plank in turn supports a spring plate 30 which is provided on its under side with a plurality of protuberances 31 which are seated within the holes 32 provided on the plank for 20 the purpose of preventing movement of said plate. The plate 30 is shaped to conform to the general outline of the shelves 16 and 17 and is further provided with a projecting tab 33 which conforms to the projecting portion 19 provided 25 on the shelf 17. A plurality of spring positioning collars 34 is also formed on the plate 30, there being more particularly seven of these collars arranged in two rows of three collars each and disposed symmetrically with relation to the 30 window opening 14, with an offset collar provided on the tab 33. In plan, therefore, the arrangement of the collars 34 presents a generally T-shaped appearance, as shown in Fig. 7, and four of said collars, denoted by the numeral 35, are formed by punching upwardly from the 35 surface of the plate 30 suitable cylindrical flanges, the other collars being constituted by the apertured sockets 36, of which there are three in number triangularly disposed with reference to each other, one of the sockets 36 being located 40 on the tab 33. Each socket 36 receives within itself the nut portion of a bolt 37 which extends upwardly through the aperture in said socket, through an enclosing spring 40, and through a 45 similar aperture formed in a similar socket 33 which is provided on a spring cap 39. According to this arrangement, therefore, the springs 40, spring plate 30 and spring cap 39 may be assembled as a unit away from the truck and 50 placed bodily in position on the spring plank.

One end of a truck bolster 41 is supported on the spring assembly above described and may include in said end a vertical strengthening web 42 which is centrally disposed with reference to 55 the sides of the bolster. In order to increase the strength of the bolster both in vertical and transverse directions, as well as to avoid the customary creation of transverse shrinkage cracks now occasioned during the cooling of the 60 standard cast bolsters by reason of the joining of thin side walls to heavy top and bottom, I propose to adopt with reference to the distribution of the metal in the sections of the bolster a plan similar to that shown with reference to 65 the section of the bottom tie member 15. According to this plan, the top 43 and bottom 44 of the bolster have a thickness which is less along the vertical neutral axes thereof than at their junction with the side walls 45. Similarly, 70 the thickness of the side walls 45 is less along their transverse neutral axes than at their junction with said bottom and top.

At a predetermined distance inwardly from each end, the bolster 41 is provided with the usual integral lugs 46 which coact with the

shoulders 47 formed on the inside of the side frame 10. A channel-shaped depression 48 is formed along each vertical side of the bolster, adjacent the end thereof, and each of which receives, when the bolster is in operating position, one end of a retaining plate 49 which is carried in a pocket 50 provided on the side frame 10 and prevented from disengaging therefrom by means of a pin 51 which passes through said plate and the walls of said pockets. As will be noted by reference to Fig. 2, the extreme width of the bolster 41 outwardly from the integral lugs 46 is less than the extreme width of the window opening 14. So that in order to remove the side frame 10, it is merely necessary to jack up the spring plank, spring assembly, and the bolster, whereupon the retaining plate 49 may be abstracted and the side frame removed. According to present methods, wherein a standard bolster is used which embodies as a substitute for the retaining plate 49 another integral lug similar to the lug 46, it is necessary to entirely remove the spring assembly and spring plank in order to permit a dropping of the truck bolster to the bottom of the window opening before the side frame can be removed. The simplicity and practical advantages of the above arrangement will therefore be apparent, the use of the retaining plate 49 not sacrificing any operating advantage which may now reside in the integral 100 lugs, since the plate adequately guides the bolster in its vertical movement, prevents outward lateral movement of the side frame, as well as tying these parts of the truck together in the event of a wreck or other unusual operating condition.

However, the use of the plate 49 does not prevent the side frame 10 from being assembled in connection with a standard bolster, as will be seen by reference to Fig. 12. The end face 111 of the outer side wall 52 of the pocket 50 has been stepped back from the sides of the window opening 14 sufficient to establish a shoulder 53 whose lateral distance from the shoulder 47 has been arranged to accommodate a standard 120 bolster having the integral lugs 46 and 54, the shoulder 53 being operatively positioned with reference to the lug 54.

From the above, it will be obvious that the bottom tie portion 15 of the tension member has 125 been adequately strengthened to resist the forces tending to deflect the same between the bolster columns 13 by reason of the enlarged spring group. Moreover, this group of seven springs has been so arranged as to render it completely 130 operative as a load-sustaining structure either as an assembly of six springs, or as an assembly of seven springs, without affecting the efficient operation of the truck. The advantages of the side frame in respect of its engagement with the truck bolster has already been noted above, as well as the availability of the frame for use in connection with a standard bolster if substitution is desired. Moreover, the outward overhang on the side frame is materially lessened over other spring groups comprising seven springs now used in the industry, since the outer shelf 16 is only required to have a depth sufficient for the diameter of one spring.

It is also contemplated that the above method of connecting the bolster and side frame may be slightly modified, for trucks employing the so-called lateral motion bolster, merely by eliminating the lugs 46 and increasing the width of the depression 48. Under these conditions, the plate 145

49 would limit endwise movement of the bolster in both directions.

While I have shown one set of elements and combinations thereof for effectuating my improved car truck, it will be understood that the same is intended for purpose of illustration only and in no wise to restrict my arrangement to the exact forms and structures shown, for many changes may be made therein without departing 10 from the spirit of my invention.

I claim:

1. A side frame comprising a bottom tie member, shelves extending laterally from said member to provide a spring plank seat, flanges projecting laterally from said member beneath said shelves and extending upward toward the bolster columns of said frame from the mid-points between said columns, and ribs connecting said shelves with said flanges at said points.
- 20 2. A side frame comprising a hollow, bottom tie member, shelves projecting laterally from said member to provide a spring plank seat, strengthening means projecting laterally from said member beneath said shelves, flanges projecting laterally within said member and extending upward toward the bolster columns of said frame from the mid-points between said columns, and ribs connecting the upper web of said member with said flanges at said points.
- 30 3. A side frame comprising a hollow, bottom tie member, shelves projecting laterally from said member to provide a spring plank seat, flanges projecting laterally from said member beneath said shelves and extending upward toward the bolster columns of said frame from the mid-points between said columns, a second group of flanges projecting laterally within said member beneath the upper web thereof and extending upward toward the bolster columns of said frame from the mid-points between said columns, and ribs connecting said shelves and said web, respectively, with said flanges at said points.
- 35 4. A side frame comprising a bottom tie member, shelves projecting laterally from said member to provide a spring plank seat, flanges projecting laterally from said member in a plane common with the lower side thereof midway between the bolster columns and bending upward toward said columns at these points, and ribs connecting said shelves with said flanges at said points.
- 45 5. A side frame comprising a hollow, bottom tie member, shelves projecting laterally from said member in a plane common with the upper side thereof to form a spring plank seat, flanges projecting laterally from said member beneath said shelves and bending upward toward the bolster columns of said frame from the mid-points between said column, and ribs connecting said shelves with said flanges at said points.
- 55 6. A side frame comprising a hollow, bottom tie member, shelves projecting laterally from said member in a plane common with the upper side thereof to form a spring plank seat, flanges projecting laterally from said member in a plane common with the lower side thereof midway between the bolster columns and bending upward toward said columns from these points, and ribs connecting said shelves with said flanges at said points.
- 60 7. A side frame comprising a hollow, bottom tie member, shelves projecting laterally from said member to provide a spring plank seat, strengthening means projecting laterally from

said member beneath said shelves, flanges projecting laterally within said member to merge with the lower side thereof midway between the bolster columns and bending upward toward said columns from these points, and ribs connecting the upper web of said member with said flanges at said points.

8. A side frame comprising a hollow, bottom tie member, shelves projecting laterally from said member to provide a spring plank seat, flanges projecting laterally from said member in a plane common with the lower side thereof at the mid-points between the bolster columns of said frame and bending upward toward said columns from said points, a second group of flanges projecting laterally within said member to merge with the lower side thereof midway between the bolster columns and bending upward toward said columns from these points, and ribs connecting said shelves and the upper web of said member, respectively, with said flanges at said points.

9. A side frame comprising bolster columns, a bottom tie member connecting said columns to partly define a window opening therewith, shelves projecting laterally from said member to provide a spring plank seat, flanges projecting laterally from said member beneath said shelves and bending upward from the mid-points between said columns to join said shelves adjacent the lower corners of said opening, and ribs connecting said shelves with said flanges at said points.

10. In a car truck, the combination of a side frame formed with compression and tension members spaced at intermediate portions thereof by bolster columns leaving a bolster opening therebetween, the tension member, beneath the bolster opening, being formed with a spring seating portion substantially T-shaped in plan, and a nest of springs supported on and having substantially the same shape in plan as said spring seating portion, the axis of the limbs of the spring nest T being in alignment with the longitudinal axis of the side frame.

11. In a car truck, the combination of a side frame formed with compression and tension members spaced at intermediate portions thereof by bolster columns leaving a bolster opening therebetween, the tension member, beneath the bolster opening, being formed with a spring seating portion substantially T-shaped in plan, and a nest of springs comprising seven springs arranged with a single spring supported on the upright of the T and the remainder on the limbs thereof, the six springs being symmetrically disposed in the bolster opening with the major axis of the latter group in alignment with the longitudinal axis of the side frame.

12. In a car truck, the combination of a side frame formed with compression and tension members spaced at intermediate portions thereof by bolster columns leaving a bolster opening therebetween, the tension member, beneath the bolster opening, being formed with a spring seating portion substantially T-shaped in plan, and a nest of springs supported on said spring seating portion comprising two rows of three springs each, arranged on the limbs of the T with a single spring lying on the upright of the T, the spring rows being symmetrically disposed on opposite sides of the longitudinal axis of the side frame.

13. In a car truck, the combination of a side frame formed with compression and tension

- members spaced at intermediate portions thereof by bolster columns leaving a bolster opening therebetween, shelves extending laterally from said portion to provide a spring plank seat substantially T-shaped in plan, flanges projecting laterally from said tension member beneath said shelves and extending upward toward the bolster columns of said flange from the mid-point between said columns, ribs connecting said shelves with said flanges at said points, and a nest of springs supported on and having substantially the same shape in plan as said seat. 14. In a car truck, the combination of a side frame formed with compression and tension members spaced at intermediate portions thereof by bolster columns leaving a bolster opening therebetween, shelves extending laterally from said portion to provide a spring plank seat substantially T-shaped in plan, flanges projecting laterally from said tension member beneath said shelves and extending upward toward the bolster columns of said frame from the mid-point between said columns, ribs connecting said shelves with said flanges at said points, and a nest of springs comprising seven springs arranged with a single spring supported on the upright of the T and the remainder on the limbs thereof. 15. A car truck side frame comprising a compression member, a tension member, and spaced bolster columns extending vertically between said compression and tension members, said tension member having a central horizontal spring supporting portion including an upper web joined at its ends with said bolster columns, a lower web spaced therefrom, vertical struts extending between the mid-points of said upper and lower webs, and inclined webs extending from said lower web in the region of the connection of said struts therewith and being joined with said upper web in the region of the connection of said upper web with said bolster columns. 16. A car truck side frame comprising a compression member, a tension member, and spaced bolster columns extending vertically between said compression and tension members, said tension member having a central horizontal spring supporting portion including spaced sides, an upper web joined at its ends with said bolster columns and at its sides with said spaced sides, a lower web joined at its sides with said spaced sides, vertical struts extending between the mid-points of said upper and lower webs, and inclined webs integral with and extending from said lower web in the region of the connection of said struts therewith and joining with said upper web in the region of the connection of said upper web with said bolster columns. 17. A car truck side frame comprising a compression member, a tension member, and spaced bolster columns extending vertically between said compression and tension members, said tension member having a central horizontal spring supporting portion including spaced sides, an upper web joined at its ends with said bolster columns and at its sides with said spaced sides, a lower web joined at its sides with said spaced sides, vertical struts extending between the mid-points of said upper and lower webs, and inclined webs integral with and extending from said lower web in the region of the connection of said struts therewith and joining with said upper web in the region of the connection of said upper web with said bolster columns. 18. A side frame having a spring seat member comprising an upper and a lower chord, and diagonal members connecting said chords and being connected to said lower chord at substantially the mid-point thereof. 19. A side frame having a spring seat member comprising an upper and a lower chord, vertical struts extending between the mid-points of said chords, and diagonal members extending from the ends of one of said chords to the region of the connection of said struts with the other of said chords. 20. A side frame having a spring seat member comprising an upper and a lower chord, vertical struts extending between the mid-points of said chord, and diagonal members extending from the ends of said upper chord to the junction of said struts with said lower chord. 21. A car truck side frame comprising a compression member, a tension member, and spaced bolster columns extending vertically between said compression and tension members, said tension member having a central horizontal spring supporting portion including an upper web joined at its ends with said bolster columns, a lower web spaced therefrom, vertical struts extending between the mid-points of said upper and lower webs, and inclined webs extending between said upper and lower webs, each inclined web being joined at one end to the upper web in the region of connection of a bolster column therewith and at the other end to the lower web in the region of connection of said struts therewith, each inclined web having spaced portions adjacent said upper web. 22. A car truck side frame comprising a compression member, a tension member, and spaced bolster columns extending vertically between said compression and tension members, said tension member having a central horizontal spring supporting portion including spaced sides, an upper web joined at its ends with said bolster columns and at its sides with said spaced sides, a lower web joined at its sides with said spaced sides, vertical struts extending between the mid-points of said upper and lower webs, and inclined webs integral with and extending from said lower web in the region of the connection of said struts therewith and joining with said upper web in the region of the connection of said upper web with said bolster columns, said inclined webs being integral at their sides with said spaced sides and having spaced portions adjacent the connections thereof with said upper web. 23. In a car truck, the combination of a side frame formed with compression and tension members spaced at intermediate portions thereof by bolster columns leaving a bolster opening therebetween, the tension member beneath the bolster opening being formed with a spring seating portion substantially T-shaped in plan, a spring plank engageable with said frame and extending substantially across the depth of said spring seating portion, and a nest of springs supported on and having substantially the same shape in plan as said spring seating portion, the axis of the limbs of the spring nest T being in alignment with the longitudinal axis of the side frame. 24. In a car truck, the combination of a side frame formed with compression and tension members spaced at intermediate portions there-

- of by bolster columns leaving a bolster opening therebetween, the tension member beneath the bolster opening being formed with a spring seating portion substantially T-shaped in plan, 5 a spring plank engageable with said frame and extending substantially across the depth of said spring seating portion, and a nest of springs comprising seven springs arranged with a single spring supported on the upright of the T and the 10 remainder on the limbs thereof longitudinally of said frame, the six springs being symmetrically disposed in the bolster opening with the major axis of the latter group in alignment with the longitudinal axis of the side frame.
- 15 25. In a car truck, the combination of a side frame formed with compression and tension members spaced at intermediate portions thereof by bolster columns leaving a bolster opening therebetween, the tension member beneath the 20 bolster opening being formed with a spring seating portion substantially T-shaped in plan, a spring plank engageable with said frame and extending substantially across the depth of said spring seating portion, and a nest of springs supported on said frame comprising two rows of 25 three springs each arranged on the limbs of the T longitudinally of said frame with a single spring lying on the upright of the T, the spring rows being symmetrically disposed on opposite 30 sides of the longitudinal axis of the side frame.
26. In a car truck, the combination of a side frame formed with compression and tension members spaced at intermediate portions thereof by bolster columns leaving a bolster opening 35 therebetween, a tension member beneath the bolster opening being formed with a spring seating portion having an offset extending inwardly therefrom, and a nest of springs comprising seven springs arranged with a single spring supported 40 on said offset and the remainder longitudinally of said frame, the six springs being symmetrically disposed in the bolster opening with the major axis of the latter group in alignment 45 with the longitudinal axis of the side frame.
27. A side frame comprising a compression member, a tension member, bolster columns interposed therebetween and spaced to define a window opening, the portion of the tension 50 member beneath said opening comprising a hollow section having side walls of less thickness at the transverse neutral axis thereof than at their junction with the bottom and top of said portion.
- 55 28. A side frame comprising a hollow, bottom tie member having side walls of less thickness at the transverse neutral axis thereof than at their junction with the bottom and top of said member, shelves extending laterally from said member to provide a spring plank seat, flanges projecting laterally from said member beneath said shelves and extending upward toward the bolster columns of said frame from the mid-points between said columns, and ribs connecting said shelves to said flanges at said points.
- 60 29. A side frame comprising a hollow, bottom tie member having side walls of less thickness at the transverse neutral axis thereof than at their junction with the bottom of said member, shelves extending laterally from said member to provide a spring plank seat, flanges projecting laterally from said member beneath said shelves and extending upward toward the bolster columns of said frame from the mid-points between said columns, and ribs connecting said shelves to said flanges at said points.
- 65 30. A side frame comprising a hollow, bottom tie member having side walls of less thickness at the transverse neutral axis thereof than at their junction with the bottom of said member, shelves extending laterally from said member to provide a spring plank seat, flanges projecting laterally from said member beneath said shelves and extending upward toward the bolster columns of said frame from the mid-points between said columns, and ribs connecting said shelves to said flanges at said points.
- 70 31. A side frame comprising a hollow, bottom tie member having side walls of less thickness at the transverse neutral axis thereof than at their junction with the bottom and top of said member, shelves extending laterally from said member to provide a spring plank seat, flanges projecting laterally from said member beneath said shelves and extending upward toward the bolster columns of said frame from the mid-points between said columns, and ribs connecting said shelves to said flanges at said points.
- 75 32. A side frame comprising a hollow, bottom tie member having side walls of less thickness at the transverse neutral axis thereof than at their junction with the bottom and top of said member, shelves projecting laterally from said member to provide a spring plank seat, flanges projecting laterally from said member beneath said shelves and extending upward toward the bolster columns of said frame from the mid-points between said columns, and ribs connecting the upper web of said member to said flanges at said points.
- 80 33. A side frame comprising a hollow, bottom tie member having side walls of less thickness at an intermediate section thereof than at their junction with the bottom of said member, shelves extending laterally from said member to provide a spring plank seat, strengthening means projecting laterally from said member beneath said shelves, flanges projecting laterally within said member and extending upward toward the bolster columns of said frame from the mid-points between said columns, and ribs connecting the upper web of said member to said flanges at said points.
- 85 34. A side frame comprising a compression member, a tension member and spaced bolster columns extending vertically between said compression and tension members, said tension member having a central, horizontal, spring supporting portion including an upper web joined at its ends with said bolster columns, a lower web spaced therefrom, vertical struts extending between the mid-points of said upper and lower webs, inclined webs extending from said lower web in the region of the connection of said strut therewith and being jointed with said upper web in the region of the connection of said upper web with said bolster columns, and side walls connecting said upper and lower webs having less thickness at the transverse neutral axis of said portion than at their junction with the bottom of said portion.
- 90 35. A car truck side frame comprising a compression member, a tension member, and spaced bolster columns extending vertically between said compression and tension members, said tension member having a central, horizontal, spring supporting portion including spaced sides, an upper web joined at its ends with said bolster columns.

tween said columns, and ribs connecting said shelves to said flanges at said points.

30. A side frame comprising a hollow, bottom tie member having side walls of less thickness at an intermediate section thereof than at their junction with the bottom of said member, shelves extending laterally from said member to provide a spring plank seat, flanges projecting laterally from said member beneath said shelves and extending upward toward the bolster columns of said frame from the mid-points between said columns, and ribs connecting said shelves to said flanges at said points.

31. A side frame comprising a hollow, bottom tie member having side walls of less thickness at an intermediate section thereof than at their junction with the bottom and top of said member, shelves extending laterally from said member to provide a spring plank seat, flanges projecting laterally from said member beneath said shelves and extending upward toward the bolster columns of said frame from the mid-points between said columns, and ribs connecting said shelves to said flanges at said points.

32. A side frame comprising a hollow, bottom tie member having side walls of less thickness at the transverse neutral axis thereof than at their junction with the bottom and top of said member, shelves projecting laterally from said member to provide a spring plank seat, flanges projecting laterally from said member beneath said shelves and extending upward toward the bolster columns of said frame from the mid-points between said columns, and ribs connecting the upper web of said member to said flanges at said points.

33. A side frame comprising a hollow, bottom tie member having side walls of less thickness at an intermediate section thereof than at their junction with the bottom of said member, shelves projecting laterally from said member to provide a spring plank seat, strengthening means projecting laterally from said member beneath said shelves, flanges projecting laterally within said member and extending upward toward the bolster columns of said frame from the mid-points between said columns, and ribs connecting the upper web of said member to said flanges at said points.

34. A car truck side frame comprising a compression member, a tension member and spaced bolster columns extending vertically between said compression and tension members, said tension member having a central, horizontal, spring supporting portion including an upper web joined at its ends with said bolster columns, a lower web spaced therefrom, vertical struts extending between the mid-points of said upper and lower webs, inclined webs extending from said lower web in the region of the connection of said strut therewith and being jointed with said upper web in the region of the connection of said upper web with said bolster columns, and side walls connecting said upper and lower webs having less thickness at the transverse neutral axis of said portion than at their junction with the bottom of said portion.

35. A car truck side frame comprising a compression member, a tension member, and spaced bolster columns extending vertically between said compression and tension members, said tension member having a central, horizontal, spring supporting portion including spaced sides, an upper web joined at its ends with said bolster columns.

- columns and at its sides with said spaced sides, a lower web joined at its sides with said spaced sides, the thickness of said sides at the transverse neutral axis of said portion being less than at their junction with said lower web, vertical struts extending between the mid-points of said upper and lower webs, and inclined webs integral with and extending from said lower web in the region of the connection of said struts there-
5 with and joining with said upper web in the region of the connections of said upper web with said bolster columns.
36. In a car truck side frame comprising a compression member, a tension member, and spaced bolster columns extending vertically between said compression and tension members, said tension member having a central, horizontal, hollow, spring supporting portion including an upper web joined at its ends with said bolster columns, a lower web spaced therefrom, side walls connecting said webs having a thickness at the transverse neutral axis of said portion less than at their junction with said lower web, vertical struts extending between the mid-points of said upper and lower webs, and inclined webs extending between said upper and lower webs, each inclined web being joined at one end to the upper web in the region of connection of a bolster column therewith and at the other end to the lower web in the region of connection of said struts therewith, each inclined web having spaced portions adjacent said upper web. 80
- 20 with said bolster columns and at its sides with said spaced sides, a lower web joined at its sides with said spaced sides, the thickness of said sides being less at the transverse neutral axis of said portion than at their junction with said lower web, vertical struts extending between the mid-points of said upper and lower webs, and inclined webs integral with and extending from said lower web in the region of the connection of said struts therewith and joining with said upper web in the region of the connection of said upper web with said bolster columns, said inclined webs being integral at their sides with said spaced sides. 85
- 25 37. A side frame having a hollow, spring seat member comprising an upper chord, a lower chord, and sides walls connecting said chords, the thickness of said side walls at the transverse neutral axis of said member being less than at their junction with said lower chord, and diagonal members connecting said chords and being connected to said lower chord at substantially the mid-point thereof. 90
- 30 38. A side frame having a hollow, spring seat member comprising an upper and a lower chord, side walls extending between said chords, the thickness of said side walls being less at the transverse neutral axis of said member than at their junction with said lower chord, vertical struts extending between the mid-points of said chords, and diagonal members extending from the ends of one of said chords to the region of the connection of said struts with the other of said chords. 95
- 35 39. A side frame having a hollow, spring seat member comprising an upper and a lower chord, side walls extending between said chords, the thickness of said side walls being less at the transverse neutral axis of said member than at their junction with said lower chord, vertical struts extending between the mid-points of said chords, and diagonal members extending from the ends of said upper chord to the junction of said struts with said lower chord. 100
- 40 40. A car truck side frame comprising a compression member, a tension member, and spaced bolster columns extending vertically between said compression and tension members, said tension member having a central, horizontal, hollow, spring supporting portion including spaced sides, an upper web joined at its ends with said bolster columns and at its sides with said spaced sides, a lower web joined at its sides with said spaced sides, the thickness of said sides at the transverse neutral axis of said portion being less than at their junction with said lower web, vertical struts extending between the mid-points of said upper and lower webs, and inclined webs integral with and extending from said lower web in the region of connection of said struts therewith and at the other end to the lower web in the region of connection of said struts therewith, each inclined web having spaced portions adjacent said upper web. 105
- 45 41. A car truck side frame comprising a compression member, a tension member, and spaced bolster columns extending vertically between said compression and tension members, said tension member having a central, horizontal, hollow, spring supporting portion including spaced sides, an upper web joined at its ends with said bolster columns and at its sides with said spaced sides, a lower web joined at its sides with said spaced sides, the thickness of said sides at the transverse neutral axis of said portion being less than at their junction with said lower web, vertical struts extending between the mid-points of said upper and lower webs, and inclined webs integral with and extending from said lower web in the region of connection of said struts therewith and at the other end to the lower web in the region of connection of said struts therewith, each inclined web having spaced portions adjacent said upper web. 110
- 50 42. A nest of springs substantially T-shaped in plan adapted for mounting in the bolster opening of an associated side frame, said nest being arranged with two rows of spring units as the limbs of the T and a spring unit offset therefrom forming the upright of the T, the spring rows being symmetrically disposed on opposite sides of the longitudinal axis of the frame. 115
- 55 43. A nest of springs substantially T-shaped in plan adapted for mounting in the bolster opening of an associated side frame, said nest comprising seven springs arranged with a single spring forming the upright of the T and the remainder of the limbs thereof, the six springs being symmetrically disposed in the bolster opening with the major axis of the latter group in alignment with the longitudinal axis of the frame. 120
- 60 65
